UNITED STATES PATENT OFFICE.

PHILIP D'HUC DRESSLER, OF CLEVELAND, OHIO, ASSIGNOR TO AMERICAN DRESSLER
TUNNEL KILNS, INC., OF CLEVELAND, OHIO, A CORPORATION OF NEW YORK.

TUNNEL KILN AND METHOD OF OPERATING SAME

Application filed July 26, 1923. Serial No. 653,892.

To all whom it may concern:

Be it known that I, PHILIP D'HUC DRESSLER, a subject of the King of Great Britain, and resident of Cleveland, in the county of 5 Cuyahoga and State of Ohio, have invented certain new and useful Improvements in Tunnel Kilns and Methods of Operating Same, of which the following is a specification.

10 My present invention relates to continuous tunnel kilns, and the general object of the invention is to make provisions for the maintenance of certain temperature conditions in the kiln which are especially desirable in annealing malleable castings.

Ordinarily in annealing malleable castings, it is desirable to heat the castings as rapidly as possible up to a certain maximum temperature and to hold them in their highly heated condition and without appreciable temperature change during a soaking period of many hours duration. The castings should then be cooled down to a temperature some hundreds of degrees below the maximum temperature and maintained without further cooling or only slight cooling for another considerable period of time comparable in duration with, though usually somewhat shorter than, the initial soaking period, 25 after which the castings are cooled down to the temperature of emergence. The initial and final cooling of the castings may be carried out rapidly without injury to the castings, and it is always desirable, of course, to make the cooling as rapid as possible since a shortening of the cooling period shortens and cheapens the construction cost of the kiln required for a given output.

In constructing a kiln in accordance with 40 the present invention, I interpose a slow cooling or low temperature soaking zone between initial and final cooling sections of the kiln, and provide means for supplying heat to said interposed zone to prevent the ware therein from being cooled as it otherwise would, as a result of radiation from the outer walls of this portion of the kiln zone and the unavoidable circulation of the kiln atmosphere. The heating means which I 45 thus add to the kiln are preferably regulable to vary the temperature conditions maintained in response to the requirements of service without interfering with the proper operation and regulation of the main kiln heating means.

The various features of novelty which characterize my invention are pointed out with particularity in the claims annexed to and forming a part of this specification. For a better understanding of the invention, 60 however, and its advantages, reference should be had to the accompanying drawings and descriptive matter in which I have illustrated and described preferred embodiments of my invention. 65

Of the drawings:

Fig. 1 is a diagrammatic plan view of an open fire kiln;

Fig. 2 is a section on the line 2—2 of Fig. 1; 70

Fig. 3 is a temperature curve;

Fig. 4 is a section on the line 4—4 of Fig. 2;

Fig. 5 is a section on the line 5—5 of Fig. 2; 75

Fig. 6 is a diagrammatic plan view partly in section of a muffle heated kiln;

Fig. 7 is a longitudinal section of the kiln shown in Fig. 6;

Fig. 8 is a transverse section of the kiln 80 shown in Fig. 6;

Fig. 9 is a temperature curve;

Fig. 10 is a partial plan section of a modified form of the kiln shown in Figs. 6, 7, and 8; 85

Fig. 11 is a partial section of the kiln shown in Fig. 10; and Fig. 12 is a view similar to Fig. 1 illustrating another modification.

Figs. 1 to 5 of the drawings show an open fire kiln A especially adapted to cause the malleable castings or other ware passing through the kiln to vary in temperature at different points along the length of the kiln in general accordance with the temperature curve t of Fig. 3. The kiln may be regarded as comprising a heating up and high temperature soaking zone a , an initial cooling zone b , a slow cooling or low temperature soaking zone c , and a rapid cooling zone d . The zone a of the kiln may be constructed and heated in any of the usual or suitable ways employed in open fire kilns in which the ware treated is maintained at or near its maximum temperature for a considerable time. In the construction shown the zone a of the kiln A is heated by means of fire boxes B suitably distributed along the length of the kiln at the sides of the high temperature end of the zone a . The heating 105

110

- gases from the fire boxes B are withdrawn from the kiln chamber proper at the entrance end of the latter through an outlet C connected to a suitable draft creating device.
- 5 As shown there are two such draft creating devices, namely, a stack E and an exhaust fan F, to either of which the outlet C may be connected by proper manipulation of the dampers D and D'.
- 10 The kiln zone b is provided with cooling means which may be of any of the known or suitable forms for cooling a portion of an open fire tunnel kiln in which the kiln temperatures are analogous to those in the 70 kiln disclosed. As shown the zone b is cooled by admitting a gaseous medium to the kiln chamber through ports G opening to the kiln chamber from vertical channels H formed in the side walls of the kiln chamber. These channels are connected at their lower ends to longitudinal channels I, one at each side of the kiln. The connection between each vertical channel H and the corresponding flue I is controlled by an individual damper D². The two flues I are both connected to a transverse flue J running under the kiln. As shown, the flue J is connected by a pipe or conduit F' to the outlet from the exhaust fan F, which thus supplies 80 warm products of combustion to the flues H, and through the ports G to the interior of the kiln chamber in the zone b. In addition to the regulation of the cooling effect in the zone b obtainable by manipulation of the 85 various dampers D², the ports G may be independently adjusted as by placing throttle brick G' of different sizes in the ports, and to permit the insertion, removal and adjustment of the throttle brick G', openings K, 90 normally closed by suitable plugs or closing devices K', are formed in the outer walls of the channels H.

Means are provided for supplying heat as required to the kiln zone c. The means shown for this purpose comprise fire boxes B' at each side of the kiln zone c, in proximity to the junction of that zone with the cooling zone b. The heating gases from the fire boxes B' are withdrawn from the kiln chamber at the end of the zone c adjacent the rapid cooling zone d, by suitable connections to a draft creating device such as the stack L. As shown, the connections between the kiln chamber and the stack L comprise vertical flues M in the side walls of the kiln chamber which are distributed along a portion of the length of the kiln, and communicate with the interior of the kiln chamber through ports N. The flues M in each side wall of the kiln, are connected at their lower ends to a corresponding longitudinal flue O, the connection between each vertical flue M and the corresponding flue O being regulated by a damper D³. The two flues O are connected to the stack L by a cross flue P.

To permit the ports N to be regulated by throttle brick, openings M' normally closed by suitable plugs or closing devices are formed in the outer walls of the flues M.

The rapid cooling zone d of the kiln may be cooled in any usual or suitable manner for effecting rapid final cooling in an open fire kiln. As shown the cooling provisions for the zone d comprise a bank of metal pipes Q at each side of this portion of the 75 kiln chamber. The tubes Q in each set are connected at their opposite ends to headers Q' and Q². The headers Q' are connected to the atmosphere, as by ports Q³, at the exit end of the kiln, and the headers Q² are connected through the ports R to a cross flue R' running to a suitable draft creating device shown as a fan S. The hot air delivered by the fan S may be used in any way in which air heated by a tunnel kiln 85 is normally used, as in heating, drying, or supplying preheated air of combustion to the fire boxes B and B'.

As shown the kiln A is provided at its entrance and exit ends with an ante-chamber A' and an exit chamber A², respectively. The chambers A' and A² may be separated from the kiln chamber proper, by doors T, and are normally closed from the atmosphere at their outer ends by doors T'. Where 95 it is desirable to avoid oxidizing conditions in the kiln chamber, the influx of air into the kiln chamber when either door T is open may be prevented by supplying a neutral gas to the ante and exit chambers either 100 constantly, or whenever necessary to prevent the passage of air from those chambers into the kiln chamber proper. For this purpose valved branch pipes F² and F³ run from the conduit F' to the chambers A' and A².

With the kiln construction described it is readily possible to cause the ware to vary in temperature as it progresses through the kiln in the manner indicated by the temperature curve t of Fig. 3. The described provisions for imparting heat to the slow cooling or low temperature soaking zone C, make it readily possible to hold the temperature of the ware constant between the points 1 and 2 on the curve, and to shift either or 110 both of these points longitudinally of the kiln. To secure the last mentioned result I vary the relative rates at which heat is supplied to the kiln chamber from the different fire boxes B' at each side of the kiln, and 115 vary the relative amounts of heating gases taken off through the different tubes M.

With the means shown for heating the zones a and c, it is possible to cool the initial cooling zone b by introducing a cooling gaseous medium directly into the kiln chamber without interfering with the operation of the heating means at either end of that zone. As far as the cooling effect in the zone b is concerned, it is immaterial whether the cool- 120 125 130

- ing agent is air or products of combustion. If air is used there would be an oxidizing effect objectionable in some cases which is avoided by the use of products of combustion 5 as the cooling agent. The preheating of the cooling agent supplied to the zone *b*, reduces the risk of unduly rapid local cooling and facilitates close regulation of the temperature in this zone of the kiln. When it is 10 neither necessary to use a heated cooling agent nor to avoid the use of a cooling agent having an oxidizing effect, the damper *D*⁴ may be closed and the damper *D*⁵ opened, to thereby disconnect the flue *J* from the outlet 15 from the blower *F* and connect it through the outlet *J'* to the atmosphere, so that atmospheric air will then be drawn into the kiln chamber through the flues *H* and ports *G*. 20 In Figs. 6, 7, and 8, I have illustrated a kiln *AA* having muffle heating provisions, and in which the ware passing through the kiln may be subjected to the temperature variations indicated in Fig. 3. In the kiln 25 *AA* heat is supplied to the heating up and high temperature zone *a* of the kiln by combustion chambers *U* located in the kiln chamber, one at each side of the goods pathway therethrough, and each extending the full 30 length of the zone *a*. The combustion chambers *U* illustrated are of the type commonly employed in Dressler tunnel kilns, the walls of each combustion chamber being formed of sections of tile extending transversely to 35 the length of the kiln and formed with open ended channels *U'* which unite to form a flue system communicating with the kiln chamber at the bottom and top of the combustion chamber, and through which a gravity circulation 40 of the kiln atmosphere is induced by the heat absorbed by the streams of the kiln atmosphere flowing upward through said flues.
- Fuel and air for its combustion are supplied to each combustion chamber *U* through burner nozzles *W* distributed along the high temperature end of the zone *a*. Products of combustion are withdrawn from each combustion chamber *U* through an outlet port 45 *U*² at the entrance end of the kiln, and a conduit *CA* by which both ports *U*² are connected to a suitable draft creating device. As shown the draft creating device employed is a fan *FA* which draws the heating 50 gases from the conduit *CA* through the hot gas passages of a recuperator *X*, and discharges them partly to an outlet stack *EA*, and partly to the pipes *F*² and *F*³ supplying products of combustion to the kiln ante and 55 exit chamber *A'* and *A*², respectively. Fuel 60 in the form of oil or gas is supplied to each of the burner nozzles *W* through a separate valved connection *W'* from fuel supply piping *W*². Air for the combustion of the fuel 65 is blown through the recuperator *X*, and

preheated therein, by a fan *Y*, and is delivered under pressure to the burner nozzles *W* through the supply pipes *X*², and a separate valved connection *X'* to each burner nozzle *W*. 70

A second pair of combustion chambers *UA* are placed one in end to end relation with each of the chambers *U* and between the latter and the exit end of the kiln. The combustion chamber extends along the full 75 length of the zone *c* of the kiln and through most of the length of the zone *b*. The combustion chambers *UA* are provided with burner nozzles *WA* similar to the nozzles *W*, and each having separate valved connections *W'* and *X'* to the fuel and air supply pipings *W*² and *X*², respectively. Preferably as shown each combustion chamber *UA* is provided with a plurality of nozzles *WA* distributed along the length of a portion of the combustion chamber *UA* adjacent the corresponding combustion chamber *U*. Products of combustion are withdrawn from the combustion chambers *UA* by means of a suitable draft creating device shown as a stack *LA* which is connected to the ends of the combustion chambers *UA* adjacent the exit end of the kiln by a suitable port and conduit arrangement. The final cooling zone *d* of the kiln *AA* may be 90 and is shown as being exactly like the final cooling zone *d* of the kiln *A*. 95

In operation, by suitably regulating the valve fuel and air supply connections *W'* and *X'* to the different burner nozzles *WA*, 100 temperature conditions in the zones *b* and *c* of the kiln may be varied to suit the conditions of operation. To cause the ware to vary in temperature as indicated by the temperature curve of Fig. 3 in passing through the zones *b* and *c* of the kiln *AA*, air but not fuel is supplied to one or more of the burner nozzles *WA* of each combustion chamber *UA* adjacent the zone *a* of the kiln, while fuel, and any additional air required for its combustion, is supplied to the burner nozzles *WA* nearer the exit end of the kiln. The air thus supplied to some of the burner nozzles *WA* without a corresponding supply of fuel thereto, acts as a cooling agent supplementing the external radiation from the kiln in effecting a comparatively rapid cooling of the ware passing through the corresponding portion of 110 the kiln. By supplying both fuel and air for its combustion in suitable amounts to the burner nozzles *WA* adjacent the zone *a*, the temperature of the ware in passing through the zones *b* and *c* may be caused to follow the temperature curve of Fig. 9. 115

In the modified form of the kiln *AA* shown in Figs. 10 and 11, the combustion chambers *UA* are located wholly within the zone *c* of the kiln, and the width of the kiln 120 is contracted in the zone *b* and the cooling 125

flues Z are formed in the side walls of this portion of the kiln. The flues Z communicate with the atmosphere through ports Z' adjacent the ground level, and at their upper ends the flues Z open into a chamber Z² in the roof of the kiln chamber proper and provided with suitable valved outlets Z³. With this arrangement the flues Z act like chimneys to move atmospheric air upward through them and thus add to the natural radiation loss of heat in this portion of the kiln chamber. The modification illustrated in Figs. 10 and 11 is well adapted for causing the ware passing through the kiln zones b and c to vary in temperature according to the temperature curve t shown in Fig. 3.

In Fig. 12, I have shown an open kiln differing from that shown in Figs. 1, 2, 4 and 5 in that the blower F and conduits F', F² and F³, and the stack L, and the flues M are omitted, and a stack LA is connected to the kiln chamber through a damper controlled conduit CA, which communicates with the kiln chamber at points intermediate the flues H and combustion chambers B'. With the stack L replaced in effect by the stack LA the direction of gas flow through the slow cooling zone of the kiln is reversed; but in a general way the same temperature conditions can be maintained as in the kiln shown in Fig. 1.

The omission of the blower F and conduits F', F² and F³ simplifies the kiln construction and is therefore desirable in cases in which the kiln chamber atmosphere control obtainable with them is unnecessary. The use or non use of the blower F and conduits F', F², and F³ obviously does not depend on whether the stack of Fig. 1, or the stack LA of Fig. 12 is employed.

Certain novel features of my invention specific to the embodiments illustrated in Figs. 7, 8, 10, 11 and 12, as distinguished from Figs. 1, 2, 3, and 5, are not claimed herein, but are claimed in my prior application, Serial No. 394,985, in which claims are also made on the provisions shown, but not claimed herein for introducing products of combustion into the kiln antechamber and exit chamber.

While in accordance with the provisions of the statutes, I have illustrated and described the best forms of my invention, now known to me, it will be apparent to those skilled in the art that many changes in form may be made without departing from the spirit of my invention, and that certain features of my invention may sometimes be employed to advantage without a corresponding use of other features.

Having now described my invention, what I claim as new and desire to secure by Letters Patent, is:

1. The method of operating a tunnel kiln which consists in maintaining a high tem-

perature zone, an initial cooling zone and a slow cooling or low temperature soaking zone in the order stated between the entrance and exit ends of the kiln by exerting a cooling effect on the rapid cooling zone portion of the kiln and supplying heat to the kiln chamber in each of the other of said zones. 70

2. The method of operating a continuous tunnel kiln comprising a heating up zone at one end, and a final cooling zone at the opposite end of an intermediate portion of the kiln, which consists in causing a heating fluid to flow through the heating zone and a cooling fluid to flow through the cooling zone, each in a direction opposite to that in which the goods pass through the kiln, and in causing a heating fluid to flow in the opposite direction through the intermediate portion of the kiln. 75

3. The method of operating a tunnel kiln which consists in supplying heating gases to the kiln at the opposite ends of an intermediate section of the kiln and moving the heating gases so supplied away from said intermediate section toward the opposite 80 ends of the kiln chamber. 90

4. The method of operating an open fired tunnel kiln which consists in supplying heating gases to the kiln chamber at the opposite ends of an intermediate section of the kiln chamber and moving the heating gases so supplied through the kiln chamber away from said intermediate section toward the opposite ends of the kiln chamber. 95

5. The method of operating an open fired tunnel kiln which consists in supplying heating gases to the kiln chamber at the opposite ends of an intermediate section of the kiln chamber and moving the heating gases so supplied through the kiln chamber 100 away from said intermediate section and toward the ends of the kiln chamber and introducing products of combustion into said intermediate section of the kiln chamber at a temperature appreciably above the temperature of the atmosphere and appreciably below the temperature in said intermediate kiln section. 110

6. The method of operating an open fire tunnel kiln which consists in passing heating gases through a heating portion of the kiln chamber and returning a portion of the heating gases leaving the kiln chamber to a cooling zone section of the kiln chamber at a temperature appreciably above that of the atmosphere but below that existing in the portion of the kiln chamber into which the gases are returned. 115

7. The method of operating an open fire tunnel kiln which consists in maintaining 120 a heating up and high temperature soaking zone, an initial cooling zone and a slow cooling or low temperature soaking zone in the order stated between the entrance and exit ends of the kiln, by introducing heating 125 130

gases into the first and third mentioned zones and introducing a gaseous cooling medium into said rapid cooling zone.

8. The method of operating an open fire tunnel kiln which consists in maintaining a heating up and high temperature soaking zone, an initial cooling zone and a slow cooling or low temperature soaking zone in the order stated between the entrance and exit ends of the kiln by introducing a gaseous cooling medium into the rapid cooling zone portion of the kiln chamber and supplying heating gases to the kiln chamber in each of the other of said zones and withdrawing the heating gases so supplied from the kiln chamber at points remote from, and at the opposite ends of said rapid cooling zone.

9. In an open fire tunnel kiln having provisions for supplying heating gases to, and moving them through the high temperature zone of the kiln chamber toward the entrance end of the latter, the improvement which consists in provisions for cooling a section of the kiln chamber immediately adjacent the high temperature zone of the kiln and between said zone and the exit end of the kiln with comparative rapidity and means for supplying heat to a second section of the kiln between the first mentioned section and the exit end of the kiln.

10. In an open fire tunnel kiln having provisions for supplying heating gases to, and moving them through the high temperature zone of the kiln chamber toward the entrance end of the latter, the improvement which consists in means for maintaining a slow cooling zone in the kiln chamber between the high temperature zone and the exit end of the kiln, and means for maintaining an initial cooling zone in the kiln between the slow cooling and high temperature zones.

11. In an open fired tunnel kiln, provisions for maintaining a high temperature and heating up zone adjacent the entrance end of the kiln, and an initial cooling zone adjacent the high temperature zone and between it and the exit end of the kiln, and a slow cooling zone between the rapid cooling zone and the exit end of the kiln, comprising means for supplying heating gases to the kiln chamber at the end of the high temperature zone remote from the entrance end of the kiln and for withdrawing said gases from the kiln at a point less remote from said entrance end, and means for supplying heating gases to the kiln chamber adjacent the end of the slow cooling zone remote from the exit end of the kiln and for withdrawing the last mentioned gases from the kiln at a point less remote from the exit end of the kiln.

12. In an open fire tunnel kiln having provisions for supplying heating gases to, and moving them through the high temperature zone of the kiln chamber toward the

entrance end of the latter, the improvement which consists in means for retarding the cooling of the ware in a portion of the kiln chamber between the high temperature zone and the exit end of the kiln, comprising provisions for supplying heating gases to the kiln chamber at the end of said portion remote from the exit end of the kiln and for moving the last mentioned heating gases through the kiln chamber toward the exit end of the latter.

13. In an open fired tunnel kiln, provisions for maintaining a high temperature and heating up zone adjacent the entrance end of the kiln, and an initial cooling zone adjacent the high temperature zone and between it and the exit end of the kiln, and a slow cooling zone between the rapid cooling zone and the exit end of the zone, comprising means for supplying heating gases to the kiln chamber at the end of the high temperature zone remote from the entrance end of the kiln and for withdrawing said gases from the kiln at a point less remote from said entrance end, and means for supplying heating gases to the kiln chamber adjacent the end of the slow cooling zone remote from the exit end of the kiln and for withdrawing the last mentioned gases from the kiln at a point less remote from the exit end of the kiln, and means for passing a gaseous cooling agent into the rapid cooling zone portion of the kiln chamber.

14. The method of operating an open fired tunnel kiln which consists in supplying heating gases to the kiln chamber at the opposite ends of an intermediate section of the kiln chamber and moving the heating gases so supplied through the kiln chamber away from said intermediate section toward the opposite ends of the kiln and introducing a gaseous cooling medium into said intermediate section.

15. The method of operating an open fired tunnel kiln which consists in supplying heating gases to the kiln chamber at the opposite ends of an intermediate section of the kiln chamber and moving the heating gases so supplied through the kiln chamber away from said intermediate section toward the ends of the kiln and introducing a gaseous cooling medium into said intermediate section of the kiln chamber at a temperature intermediate the temperature of the atmosphere and the temperature in said intermediate section.

16. In a continuous tunnel kiln, the combination with a chamber comprising a heating zone at one end and a final cooling zone at the opposite end of an intermediate portion of said chamber, of means for causing heating gases to flow through the heating zone in one direction and for causing a cooling fluid to flow in the same direction through the cooling zone, and for causing

a heating fluid to flow in the opposite direction through said intermediate kiln portion.

17. In a continuous tunnel kiln, the combination with the kiln chamber and means for supplying heat to a heating up zone or section of the kiln chamber, of means for optionally supplying heat to or abstracting it from an adjacent cooling zone or section 10 of the kiln as required to regulate the temperature therein.

18. In a continuous tunnel kiln, the com-

bination with the kiln chamber and means for supplying heat to one end portion and for abstracting heat from the opposite end 15 portion of the chamber, of means for optionally supplying heat to or abstracting it from an intermediate portion of the kiln chamber as desired.

Signed at Cleveland in the county of 20 Cuyahoga and State of Ohio this 23rd day of July A. D., 1923.

PHILIP D'HUC DRESSLER.
